C. MATHIEU.

BALANCING TOY.

APPLICATION FILED SEPT. 30, 1920.

1,384,476.

Patented July 12, 1921.

By his Attorney
Maurice Block

UNITED STATES PATENT OFFICE.

CHARLES MATHIEU, OF NEW YORK, N. Y.

BALANCING TOY.

1,384,476.

Specification of Letters Patent. Patented July 12, 1921.

Application filed September 30, 1920. Serial No. 413,905.

To all whom it may concern:

Be it known that I, CHARLES MATHIEU, a subject of the King of Italy, residing at New York city, Bronx county, and State of New York, have invented certain new and useful Improvements in Balancing Toys, of which the following is a full, clear, and exact description.

This invention relates to improvements in balancing toys, one of the objects being to provide a toy of this nature which will afford amusement to children and at the same time be inexpensive and easily manufactured. A further object of the invention is to provide a toy to simulate a tight-rope walker, even to the extent of the natural use of the arms to maintain equilibrium.

To carry out my invention I resort to novel means to actuate the arms to operate them in such manner as to convey the idea that they are being used to maintain balance.

I will now proceed to describe my invention in detail, the novel features of which I will finally hereinafter claim, reference being had to the accompanying drawing, wherein—

Figure 1 illustrates my invention in elevation;

Fig. 2 is an enlarged end view, the skirt being shown in section and the weight-carrying-rod broken off;

Fig. 3 is a sectional plan view on line 3—3 in Fig. 2;

Fig. 4 is a fragmentary side view illustrating a portion of the body and a portion of one of the legs;

Fig. 5 is a sectional plan view on line 5—5 Fig. 2; and

Fig. 6 is a fragmentary perspective view of the upper end of the weight-carrying-rod or support for the figure.

As herein illustrated, my invention is made up of a figure 7 to represent (for instance) a tight-rope walker, said figure consisting of a body portion 8 having legs 9 and 10 and arm members 11 and 12, preferably made in one piece, said figure being also provided with a short skirt 13. In combination with the figure I provide a grooved wheel 14 connected to the body by a supporting rod 15, the upper end of which is formed into a T head 16 to engage openings 17 and 18 in the leg-members 9 and 10, respectively. It will be seen that the body

8 is made up of two members or sheets 19 and 20 and that the support 15, at its upper portion, is held between said sheets or members. The head 16 is formed to provide recessed portions 21 in each arm 16a thereof to receive the longitudinal edges 22 of the slots 17 and 18 of the leg-members 9 and 10. The outer end of arms 16 of the head is enlarged to provide a stop, and the head intermediate its ends is also enlarged, as at 23, to engage an opening 24 formed in the body 8. By means of the head just mentioned the support 15 is held in position and the legs 9 and 10 slidably connected to the body member 7. The body member is further provided with a transversely disposed member 25 shaped to form the arms 11 and 12.

Intermediate its ends the member 25 is provided with notches 26 and 27, said notched portions being engaged by the body member 7. To connect the body member and arm member I provide the body member with an opening 28 through which member 25 is slipped until the notches 26 and 27 engage same. The member 25 is loosely mounted in slot 28 and is free to move or swing in a vertical plane when acted upon by legs 9 and 10.

To connect the grooved wheel 14 and the support 15, I provide support 15 with a loop or eye 29 which is engaged by axle member 30 of wheel 14. The eye or loop 29 will be formed by passing the wire out of which support 15 is formed around axle-member 30. The support 15 will be offset, as at 31, to escape the cord 32. The lower end of support 15 carries a balancing weight 33. Each leg 9 and 10 is provided with a slot 34 to receive pins 35 carried by wheel or roller 14.

When the figure is placed upon the cord 32, said cord being angularly disposed, the figure will roll along same and be maintained in a vertical position by the weight 33. The grooved wheel 33 will of course engage the cord (see Fig. 2). During the movement of the toy along the cord the legs 9 and 10 will be raised and lowered alternately, and consequently the arms 11 and 12 will be moved upwardly and downwardly, for the reason that the upper end of each leg-member will strike its adjacent arm-member, thereby raising said arm-member (as indicated by full lines in Fig. 2) alternately. The arm-members 11 and

12 when in motion will have the appearance of being used for balancing purposes, thereby lending to the figure additional attraction as a toy.

5 Having now described my invention, what I claim is:

1. In a balancing toy, a body member, a pair of aligned connected arms movably mounted on the body member and normally 10 extending outwardly therefrom, legs also slidably connected to said body member, the upper end of each leg alternately striking said arms, and a roller connected to the body member and arranged to move the leg members.

2. In a balancing toy, a body member, a one-piece member extending transversely of the body member and loosely mounted thereon and representing arms, leg members slidably connected to the body member and 20 movable in a vertical plane, the upper ends

of the leg members alternately striking the transversely disposed arm member to wave its arms, and means connecting said leg members to a roller to impart to the leg members a vertical movement, the roller being connected to the body member. 25

3. In a balancing toy, a body member having a slot, a one-piece arm member having recesses at opposite edges and intermediate 30 the ends thereof, that portion of the body member adjacent the slot therein being located in said recesses, and vertically movable legs carried by the body member, the upper ends of the legs alternately striking 35 the movable arm-members.

Signed at New York city, N. Y., this 28th day of September, 1920.

CHARLES MATHIEU.
